Attorney.

UNITED STATES PATENT OFFICE.

WILLIAM H. RODEFELD AND EDWARD F. RODEFELD, OF RICHMOND, INDIANA, ASSIGNEES, BY DIRECT AND MESNE ASSIGNMENTS, TO OSHKOSH AUTOMOTIVE PRODUCTS COMPANY, OF OSHKOSH, WISCONSIN, A CORPORATION.

TIMING DEVICE.

Application filed February 27, 1924. Serial No. 695,460.

The object of our present invention, broadly speaking, is to provide a timing device which is simple in character, positive in action, light in weight, easily operated and controlled, affording a maximum of efficiency in practice, and which can be manufactured, sold and installed at a comparatively low price.

More specifically stated, our object is to provide an electric timing device for automobile motors or the like, by means of which an engine is timed to fire in proper sequence, with proper electrical potential provided progressively to cause proper ignition in the various cylinders, which in this instance we will assume to be four in number.

Various other objects and particular advantages of our invention will suggest themselves in the course of the following description, and that which is new will be correlated in the claims.

The proposed means for carrying out the principles of our invention in a practical manner is shown in the accompanying drawings, in which—

Figure 1 is a perspective view of the body or case assembly. Figure 2 is a plan view, showing the interior of the case assembly, and with the brush assembly in operative position in connection therewith. Figure 3 is a perspective view of the brush assembly alone. Figure 4 is a central cross-section taken through the case assembly alone. Figure 5 is a central cross section of the case assembly, showing the brush assembly in connection therewith, and showing other parts to which the case assembly and the brush assembly are connected. Figure 6 is an outside plan view of the closed end of the case assembly. Figure 7 is an end elevation of the brush holder without the brush, showing an end of the shaft on which the holder is secured. Figure 8 is a perspective view of the brush alone. And Figure 9 is a longitudinal central section of the brush.

Similar indices denote like parts throughout the several views. In order that the construction, the operation, and the several advantages of the invention may be more fully understood and appreciated, we will now take up a detailed description thereof, in which we will set forth the same as comprehensively as we may.

The invention comprises three distinct

groups of elements: The case assembly; the brush assembly; and the supporting members, which for convenience we will describe in reverse order.

The supporting members includes the motor casing A, a portion only of which is shown. The shaft B which protrudes from the side or face of the casing A, and it operates revolvably in any well known manner. In the side of the casing A a circular indentation C is formed concentric with the shaft B. For the purpose hereinafter shown the outer portion of the shaft B is formed with a shoulder α , and a nut D is threaded on the outer end of said shaft. Letter E designates a spring-arm, one end of which is secured to the casing A, while the other or free end is adapted to retain our device in operative position, as hereinafter set forth.

The brush assembly comprises a hub 1, which is adapted to fit the outer end portion of the shaft B, where it is retained by the nut D by which it is made tight against the shoulder α . A notch 2 is formed in the end of the hub 1 to receive a pin 3 into the shaft at the proper point to properly retain the hub in position.

Formed integral with said hub, and curving toward each other from two opposite sides of the hub, are the arms 4 and 4', whose free terminals are directed toward each other a short distance to one side of the hub, the ends of said arms being in the nature of jaws, as shown, and for the purpose hereinafter set forth. Extending out from the central portion of the hub and located midway of the arms, is a round boss 5 around which may fit the inner end of the helical spring 6.

The brush proper is in the nature of a block having a convex face 7, and on the opposite side therefrom a concave face 8, both of which faces extend longitudinally of the brush and substantially parallel with each other. Extending into and through the center of the face 7, parallel with the hub, is the channel 9. The sides 10 and 11 of the brush are parallel with each other and they connect the faces 7 and 8, being at right-angles thereto. The ends of the brush are formed each with a pocket, 12 and 13 respectively, to receive the jaws or free ends of the arms 4 and 4', as shown. Said pockets are each formed by two side flanges and a base flange, the latter

being adjoining the ends of the concave surface 8. Formed in the center of the concave face 8 is a socket 14 to receive the outer end of the spring 6.

5 The brush as set forth is adapted to be slid sidewise between the arms 4 and 4' while the face 8 is in contact, or nearly so, with the hub, after which the brush is moved outward, thereby causing the jaws of said arms 10 to enter their respective pockets 12 and 13 until the said jaws engage with the base flanges of said pockets. While in this latter position the spring 6 may be compressed and inserted between the hub and the face 15 8, thereby causing the outer end of the spring to enter the socket 14, with the inner end of the spring located around the boss 5. Said spring is of such tension as to keep the brush outward to its limit, but permitting it to be 20 pressed inward against the resiliency of the spring, for the purpose hereinafter made apparent.

The case assembly comprises a metal cup-shaped member or shell 15, with its larger 25 and open end terminating in a flange 16 which is adapted to rotate in the depression C in which it fits. The outer closed end of the shell is provided with a small socket 17, concentric with the shaft B, in which rests the 30 knob e carried by the arm E, whereby the shell is retained in rotatable contact with said depression C of the motor. An arm 18 projects from the shell 15, which is integral therewith, to provide means whereby the shell may 35 be manually, or otherwise rotated to adjusting the timing.

Formed around on the inner periphery of the shell is a circular raceway which is divided by equally spaced notches 19, 20, 21 and 22 into (in this instance) four grounding contact faces 23, 24, 25 and 26, all of which are integral with the shell 15, and through it are electrically contacted with the motor A, and therefore grounded. Located in each of 40 the notches 19, 20, 21 and 22 is an insulated contact 31, 32, 33 and 34 respectively, that is they are insulated from the shell by the respective insulators 27, 28, 29 and 30. Integral with the respective contact members are the stems 35, 36, 37 and 38, which extend out through apertures therefor in the shell, being insulated therefrom by the insulators 39, 40, 41 and 42, respectively. Each of said stems is threaded and provided with a 45 nut, 43, 44, 45 and 46, respectively by which the respective members 31, 32, 33 and 34 are retained rigidly in position in their respective notches. And the outer end of each of said stems is provided with a knurled nut, 47, 50 48, 49 and 50, for retaining the respective wires 51, 52, 53 and 54, as hereinafter referred to.

The faces of the members 31, 32, 33 and 34 are formed concave to correspond with the 55 faces 23, 24, 25 and 26, and they are all in

circular alignment with each other, but spaced apart, whereby the said faces together form a complete circle on which may slide the face 7 of the brush, as shown in Fig. 2.

Numeral 55 denotes simply a breathing 70 aperture for the passage of air to and from the interior of the casing.

In practice the interior of the casing, except said faces forming the raceway, is covered with insulating material, such as shellac 75 or the like.

Operation:—The operation of our device will now be fully comprehended, it being understood that the case assembly is relatively stationary, also that the wires 51, 52, 53 and 54 are insulated until each in turn is grounded through connection with one of the faces 23, 24, 25 and 26, and therefore no spark will occur in the cylinders of the motor until such grounding has been made. To effect such 85 grounding progressively and in proper time is, of course the primary object of this invention.

It will now be seen that as the shaft B revolves it will carry the brush around whereby it will alternately contact with a grounding surface and at the same time with an insulated surface, contacting with all of said surfaces in each cycle of rotation. Also that in its cycle of rotation the brush will connect progressively each of the surfaces of the insulated contact members 31, 32, 33 and 34 with one of the grounded surfaces 23, 24, 25 and 26. Therefore when the brush is in contact with one of grounding contact surfaces and with the surfaces of one of the insulated members at the same time then of course the wire leading from that particular insulated member will have a grounded terminal, thereby causing a spark 100 in the particular cylinder which that wire controls.

In other words, stated briefly, the device is primarily intended to progressively cause 110 each of the insulated members, and therefore the wires 51, 52, 53 and 54, to be grounded, one at a time, during each cycle of the brush.

We desire that it be understood that various changes may be made in the various details of construction herein shown and described without departing from the spirit of the invention and without sacrificing any of the advantages thereof which are new and useful and which involves invention.

Having now fully shown and described our invention, what we claim and desire to secure by Letters Patent of the United States, is—

1. A timing device comprising a case assembly having a circular raceway therein, a brush-holder rotatable within said raceway but spaced therefrom, a contact brush carried by said brush-holder and adapted to travel in said raceway, said brush having a transversely divided face and with a pocket formed in each end of the brush, said pockets being 125 130

formed each by side flanges and a base flange integral therewith, a spring disposed between said brush and a part of the brush holder to retain the brush in contact with said raceway and thereby cause the brush to follow irregularities in the surface of the raceway as it moves therearound, substantially as set forth.

2. A timing device including a one-piece brush member having a convex outer face divided by a transverse groove and having a concave inner surface with a depression in its center to provide a spring seat and having ends with a guide flange at each side of each end and a stop flange at the inner edge of each end thereof, all substantially as set forth.

3. A timing device comprising a case, a circular raceway formed inside the case, stationary contacts located in the raceway and

forming a part thereof, a brush-holder rotatably operative within and concentric with said raceway, a contact brush carried by said brush-holder and adapted to travel on said raceway, said brush being in the nature of a segmental block having a convex face on one side and a concave face on its other side with both of said faces extending longitudinally of the brush and substantially parallel with each other and connecting the two sides of the brush, there being a channel formed in the center of the convex face and extending the full length of the brush and connecting said sides, each of the ends of the brush being formed with two side flanges and a base flange whereby a pocket is formed in each end of the brush for the purpose set forth.

WILLIAM H. RODEFELD.
